UNITED STATES PATENT OFFICE.

SIDNEY C. CARPENTER, OF WEST HARTFORD, CONNECTICUT.

PUMP AND VALVE-CONTROLLING MECHANISM THEREFOR.

No. 842,080.

Specification of Letters Patent.

Patented Jan. 22, 1907.

Application filed May 10, 1906. Serial No. 316,216.

To all whom it may concern:

Be it known that I, SIDNEY C. CARPENTER, a citizen of the United States, residing at West Hartford, in the county of Hartford 5 and State of Connecticut, have invented certain new and useful Improvements in Pumps and Valve-Controlling Mechanism. Therefor; and I do declare the following to be a full, clear, and exact description of the invention, 10 such as will enable others skilled in the art to which it appertains to make and use the same.

This invention relates to improvements in pumps and valve-controlling mechanism for 15 fire service for automobiles or other vehicles.

The object of the invention is to provide an efficient and reliable rotary pump and a valve-controlling mechanism whereby it will be impossible to shut off the hose-lines while 20 the engine and pump are still running or to start the engine and pump while the hose-lines are closed.

A further object is to provide means whereby when two hose-lines are supplied by 25 the pump either one of said lines may be cut off without stopping the engine.

With the above and other objects in view the invention consists of certain novel features of construction, combination, and arrangement of parts, as will be hereinafter 30 described and claimed.

In the accompanying drawings, Figure 1 is a plan view of the invention, parts being shown in section. Fig. 2 is a side view of the 35 same. Fig. 3 is a vertical cross-sectional view on the line 3 3 of Fig. 1, parts of the front dash or fender-plate being broken away. Fig. 4 is an enlarged sectional view of the throttle-valve and its operating mechanism for one of the pumps. Fig. 5 is a detail longitudinal sectional view through the 40 pump-casing, showing the construction of the pump-piston therein; and Fig. 6 is a cross-sectional view of the same.

Referring more particularly to the drawings, 1 denotes the frame of an automobile or other vehicle on which the apparatus is mounted. On the frame 1 at opposite sides near the front end of the same is mounted an 45 engine 2, which may be of any suitable type, but which is preferably in the form of a Cooley rotary engine. Each of said engines is provided with a steam-supply pipe 3 and an exhaust-pipe 4. Supported upon the 50 frame of the vehicle and connected with each of the engines 2 is a pump 5, said pumps be-

ing preferably, but not necessarily, of the rotary type and consist of a casing 6, through which the shaft of the engine projects and in which on said shafts are mounted pistons 7. 60 These pistons are here shown as being provided with a series of radially-disposed wings or blades 8.

To the rear ends of the pump-casing 6 are connected water-supply pipes 9, the opposite ends of which project beyond the opposite sides of the vehicle and are provided with hydrant connections 10. To the opposite ends of the pump-casing 6 are connected discharge-pipes 12, each of said pipes being here 70 shown as separated at their discharge ends to form two discharge passages or openings for each pipe. To each of the discharge openings or passages of the discharge-pipe 12 is connected a cut-off valve 13 and a hose-line connection 14. The stems of each of the valves 13 project upwardly and are provided with beveled gear-pinions 15, with which are adapted to be engaged gear-pinions 16, fixed on the front end of operating-shafts 17, which extend rearwardly and are provided on their opposite ends with hand-wheels 18, by means of which the valves in the discharge-pipes of the pump may be controlled. 80

The steam-supply pipes from the engine on each side of the vehicle extend rearwardly and downwardly and are connected with the common steam-supply pipe 19, which runs to the boiler 20, arranged in the rear end of 90 the vehicle. In each of the steam-supply pipes 3 is arranged a throttle-valve casing 21, in which is arranged a throttle-valve 22, which is mounted upon the lower reduced end of the valve-stem 22^a and is adapted to be 95 brought into engagement with valve-seats 23, formed in the valve-casing 21, as shown. Between the upper end of the valve 22 and the shoulder formed by the reduced end of the valve-stem is arranged a coil-spring 24, the object of which is to prevent the jamming of the valve upon the seats 23 when the former is brought to a closed position. The valve-casing 21 is also provided with a relief check-valve 21^a, arranged in one side thereof, as 100 shown.

The stem 23 of each of the valves 22 extends upwardly through a suitable guide-bracket 25 and is provided on its upper end with a collar 26, between which and the bracket 25 110 is arranged a coil-spring 27. The tension of said spring is exerted to hold the valve 22 in

an open position. Pivotally connected to the upper end of the stem 23 is a lever 28, to each end of which is pivotally connected short links 29, which are in turn pivotally connected to the lower end of vertically-disposed plunger-pins 30, slidably mounted in suitable guide-brackets 31, as shown. Above the brackets 31 are pivoted segmental worm-gears 32, on the lower sides of which are formed cams 33, adapted to be engaged with the upper ends of the plunger-pins 30 when said worm-gears are turned in the proper direction, thereby forcing the plunger-pins downwardly and actuating the lever 28. Fixedly mounted upon the shaft 17 of each hose-line-valve-controlling mechanism is a worm 34, said worm being adapted to engage the worm-gears 32 and to turn the same in one direction or the other when said shafts 17 are turned to open or close the hose-line valve.

By this construction it will be seen that when one or the other of the hose-line valves on either side of the apparatus is closed through the shaft 17 connected therewith said shaft through its worm 34 will turn the worm-gear 32 connected therewith, causing the cam thereon to force the plunger with which it is engaged downwardly, thus rocking the valve-lever 28 loosely on its pivotal connection with the valve-stem 23 without moving said stem or valve, thus permitting the pump to still continue the supply of water to the other pipe connection of this side of the apparatus. As soon, however, as the opposite hose-line valve of this side of the apparatus is closed through the opposite shaft 17 the gears connected with this shaft will cause the cam thereon to force down the plunger-pin connected with the opposite end of the valve-lever 28, which will necessarily force the valve-stem 23 downwardly against the tension of the spring 27 and close the throttle-valve, thus cutting off the supply of steam to the engine on this side of the apparatus and stopping the pump. When both the hose-line valves have thus been shut off and the throttle-valve closed it should be desired to use but one pipe-line, the shaft 17 connected with the valve thereof may be turned to open said valve, and thereby simultaneously operate the gears connected therewith, which will turn the cam on said gears in a direction to release the plunger-pin engaged therewith, thus permitting the spring 27 on the throttle-valve stem to rock the valve-lever 28 upwardly, allowing the throttle-valve to open and supply steam to the engine, which will cause the pump connected therewith to force water through the open pipe-line, as will be understood. The valve-operating mechanism connected with the opposite end of the lever may be turned to open the other pipe-line valve when desired, so that water will be supplied to both the

pipe-lines on this side of the apparatus. It will be understood that the throttle-valve for the engine and pump on the opposite side of the apparatus is provided with similar controlling mechanism connected with the operating-shafts 17 for the pipe-line valves on this side.

Arranged in rear of the throttle-valve-controlling mechanism is a vertically-disposed fender-plate or dash 35, through which the ends of the valve-operated shafts 17 are passed, as shown. The dash 35 being preferably provided with sliding doors 36, arranged on each side thereof, permits access to the throttle-valve-controlling mechanism in the rear of the same. The boiler 20 may be of any suitable type and arranged on the frame of the vehicle in any suitable manner, said boiler being shown in the drawings in dotted outline in an upright form.

From the foregoing description, taken in connection with the accompanying drawings, the construction and operation of the invention will be readily understood without requiring a more extended explanation.

Various changes in the form, proportion, and the minor details of construction may be resorted to without departing from the principle or sacrificing any of the advantages of this invention as defined by the appended claims.

Having thus described my invention, what I claim as new, and desire to secure by Letters Patent, is—

1. In an apparatus of the character described, the combination with an engine, of a pump operated thereby, valved discharge-pipes connected with said pump, pipe-line connections arranged on said valved discharge-pipes, an operating device connected to the valve in each of said discharge-pipes, a steam-supply pipe for said engine, a throttle-valve arranged in said pipe, an operating mechanism for said valve, and means actuated by the operating devices of said discharge-valves to close said throttle-valve when both of the discharge-valves are closed, substantially as described.

2. In an apparatus of the character described, the combination with an engine, of a pump operated thereby, valve-discharged pipes connected with said pump, pipe-line connections arranged on said valved discharge-pipes, an operating device connected to the valve in each of said discharge-pipes, a steam-supply pipe for said engine, a throttle-valve arranged therein, a spring to hold said valve open, a closing-lever connected to the stem of said valve, and means actuated by the operating devices of said discharge-valves to operate said closing-lever and thereby shut off said throttle-valve when both said discharge-valves are closed, substantially as described.

3. In an apparatus of the character de-

- scribed, the combination with an engine, of a pump operated thereby, valved discharge-pipes connected with said pump, pipe-line connections arranged on said valved discharge-pipes, operating-shafts connected to the valve in each of said discharge-pipes, a steam-supply pipe for said engine, a throttle-valve arranged in said pipe, a spring arranged on the stem of said throttle-valve to open the same, a closing-lever pivotally mounted on the upper end of said throttle-valve stem, plunger-pins loosely pivoted on the ends of said lever, pivotally-mounted segmental worm-gears, cams arranged on said gears to engage said plunger-pins thereby forcing said closing-lever down, and worms arranged on the operating-shafts of said discharge-valves to engage said segmental worm-gears, substantially as described.
4. In an apparatus of the character described, the combination with an engine, of a pump operated thereby, said pump comprising a casing, a rotary piston arranged therein and mounted on the extended end of said engine-shaft, radially-projecting blades or wings arranged on said piston, a water-supply pipe and water-discharge pipes connected to said pump-casing, cut-off valves arranged in said discharge-pipes, hose-line connections formed on the casings of said valves, bevel gear-pinions mounted on the stems of the latter, valve-operating shafts, bevel-pinions mounted thereon to engage the pinions on said valve-stems, a throttle-valve to control the admission of steam to said engine, a spring to open said valve, a closing-lever pivotally connected to the stem of the same, slidably-mounted plunger-pins, links to connect the latter to each end of said lever, pivotally-mounted worm-gears, cams formed on the latter to engage said plunger-pins and thereby actuate said closing-lever, and worms
- arranged on the operating-shafts of said discharge cut-off valves, whereby when both of said valves are closed said throttle-valve will also be closed, substantially as described.
5. In a wheeled fire-service apparatus, the combination with engines arranged thereon, of pumps operated by said engines, water supply and discharge pipes connected to said pumps, each of said discharge-pipes having one or more discharge-passages, a valve-casing connected with each of said passages, cut-off valves arranged in said casings, pipe-line connections formed on the latter, a bevel gear pinion secured to the stem of each of said valves, valve-operating shafts, gear-pinions mounted thereon to engage the pinions on said valve-stems, a steam-supply pipe having branches leading to each of said engines, a throttle-valve casing arranged in each of said branch steam-pipes, a throttle-valve, and a relief-valve arranged in said casings, a spring arranged on the stem of each of said throttle-valves to open the same, a closing-lever pivotally mounted on each of said stems, plunger-pins loosely connected to the ends of said levers, guide-brackets to slidably support said pins, pivotally-mounted worm-gears, cams formed thereon to engage said pins, worms arranged on the operating shafts of said discharge-valves to engage said worm-gears, a fender-plate or dash, and doors arranged therein to permit of access to said throttle-valve-controlling mechanism, substantially as described.
- In testimony whereof I have hereunto set my hand in presence of two subscribing witnesses.
